CLAIM

I claim the ornamental design for a hoof boot body, as shown and described.

DESCRIPTION

FIG. 1 is a front perspective view of the hoof boot body;

FIG. 2 is a rear view thereof;

FIG. 3 is a side view thereof, the opposite side view being a mirror image; and,

FIG. 4 is a top view thereof.

The portions shown in broken line are for illustrative purposes only and form no part of the claimed design.
